MODULATION SYSTEM AND METHOD

William E. Bradley, Springfield Township, Montgomery County, Pa., assignor to Philco Corporation, Philadelphia, Pa., a corporation of Pennsylvania

Application November 20, 1947, Serial No. 787,043

16 Claims. (Cl. 332—5)

1

The invention herein described and claimed relates to improved methods of and means for producing modulated carrier wave signals. More specifically, it is intended to provide a method of and means for effecting highly linear modulation of high frequency carrier wave signals, particularly in the so-called microwave range, by signals comprising a wide band of frequencies representative of intelligence to be transmitted, and adapted to provide unusually high output power with a high degree of efficiency.

In the past, numerous unsuccessful attempts have been made to provide a modulator having these characteristics and adapted to provide a modulated signal having a carrier frequency in the microwave range. This is particularly desired because of the more ready availability of channels in that range, the high directionality of antennas which can be constructed for operation at such frequencies and the favorable propagation characteristics at these frequencies. All of these factors render operation in this range desirable for numerous applications and particularly in the relaying of wideband intelligence between more or less distantly spaced transmitting and receiving stations. This latter application has arisen particularly in connection with the need for means to relay television signals between cities displaced, one from the other, by relatively large distances.

The means presently available for generating power at frequencies in the microwave range are relatively limited in number and, to date, have proven somewhat inflexible in their application. For example, a principal source of high power oscillations in the microwave range at the present time is the well-known cavity magnetron. Although this device possesses the advantage of being able to generate large amounts of power at frequencies in the microwave range, the means which have been developed in the past to effect modulation of the output energy from a magnetron oscillator have been subject to a number of serious shortcomings.

It is known to pulse-modulate the output from a magnetron oscillator by the simple expedient of varying the anode voltage thereof in response to a signal comprising time-spaced electrical pulse signals. Moreover, it is known to vary the spacing of the modulating pulses in response to intelligence desired to be transmitted, whereby to produce a high power, microwave frequency, carrier wave signal, modulated in response to such intelligence. This method of modulation, however, possesses the disadvantage that it is extremely limited as to the frequency bandwidth of the intelligence which can thus be transmitted. For example, it has been impossible, in this manner, to modulate a magnetron oscillator with intelligence comprising a band of

2

10 frequencies as broad as that required for television purposes (i. e. 4 megacycles).

More recently, also, magnetron oscillators have been developed whose output frequencies can be deviated throughout comparatively wide ranges. For example, it is known to construct magnetrons capable of oscillating at frequencies of the order of 4,000 megacycles, deviable throughout a range as large as 8 megacycles and presenting a high input impedance to the signal applied to effect deviation. These results are achieved using arrangements in which electron beams of controllable intensity, in addition to the one which participates in the production of oscillations, are caused to flow in one or more of the magnetron cavities in paths which are essentially spiral about axes perpendicular to the direction of the electric fields within said cavities and in regions where said fields are of greatest intensity. Varying the intensities of these beams produces variations in the tuning of the cavities, and thus varies the frequency at which the magnetron oscillates. Unfortunately, the linearity of the relationship between the applied modulating signal and the frequency of the output signal generated by such magnetrons is not adequate for many applications.

Accordingly the principal objects of the invention are the following:

30 (1) To provide a method of and means for effecting frequency modulation of carrier wave signals in the super-high frequency or microwave range by relatively wideband modulating signals, with a high degree of linearity and so as to produce, with high efficiency, a large output of modulated power;

35 (2) To provide an improved method of and means for frequency-modulating oscillators—particularly cavity magnetrons—with a high degree of linearity;

40 (3) To provide an improved method of and means for converting a frequency-modulated carrier wave signal of relatively low carrier frequency into a similarly modulated carrier wave signal of appreciably higher carrier frequency; and

45 (4) To provide a method of and means for converting a frequency-modulated carrier wave signal of appreciably higher carrier frequency; larly modulated carrier wave signal of a different carrier frequency, without the necessity for first demodulating the original carrier wave signal, said method and means being especially suited for use in high frequency radio relay chains employing a plurality of relay stations, each receiving a modulated carrier wave signal of a particular carrier frequency and transmitting a similarly modulated carrier wave signal of a different carrier frequency.

50 As is well recognized, if two electrical wave

signals of specified frequencies are mixed or heterodyned by the employment of any known form of mixer, there results a signal comprising a spectrum of components which, among others, include components of various frequencies which are, respectively, the sums and differences of the higher of the original frequencies and an integral multiple of the lower of said frequencies. If one of the original signals (e. g. the lower in frequency) is frequency-modulated, a similar spectrum results in which the component, whose frequency is that of the original signal of higher frequency, is of substantially constant frequency, while the components corresponding to the sums and differences of the higher original frequency and integral multiples of the lower (modulated) frequency vary in frequency in substantial accordance with the variations in the latter frequency. This phenomenon provides the basis for a method of converting a frequency-modulated carrier wave signal of a particular carrier frequency into a similarly modulated carrier wave signal of a different carrier frequency. Each of the sideband components (whose mean frequency is equal to the sum or difference of the higher original frequency and an integral multiple of the mean value of the lower, modulated original frequency) will be frequency-modulated in some degree in accordance with the modulation of the original signal of lower frequency. In general, the variations in frequency of the sideband components will be proportional to those of the original frequency-modulated signal, but the amount of deviation in frequency will differ depending on the order of the sideband. Thus, the deviations of the first upper and lower sidebands may be about the same as the deviations of the original signal, while the deviations of the higher-order sidebands may be substantially greater. The energy comprised in any one of these components may be utilized as the desired frequency-modulated output, whose mean frequency differs from that of the original modulated signal.

In thus utilizing the phenomenon, however, it is to be borne in mind that the energy represented by any one of these components will be small compared to the total energy represented by all of the components in the spectrum. Moreover, in general it will be substantially less than the component whose frequency is relatively fixed and equal to the higher of the original frequencies. Accordingly, if, as proposed above, one of the sideband components is used as output, the efficiency of the system will be comparatively low.

It is a feature of the invention that it makes it possible to overcome this disadvantage of heterodyne modulation and to provide modulating systems which incorporate the advantages of this method and which at the same time are highly efficient.

According to the invention it is proposed, by suitable means, to lock, or to maintain substantially fixed, the frequency of one of the sideband components, which, as above pointed out, will normally vary in frequency in the same manner as the lower in frequency of the input signals supplied to the mixer. When this is done, the carrier component of the spectrum will no longer continue to remain fixed in frequency, but will itself vary in some degree in accordance with the modulation of the lower in frequency of the input signals to the mixer, the degree of variation being dependent upon several factors, including the effectiveness of locking of the particular sideband

component. This being the case, the carrier component may now be used as the desired frequency-modulated output, and, since the fraction of the total power in the spectrum represented by this component is substantially greater than that represented by any of the sideband components, the efficiency of the system will be correspondingly enhanced.

As contemplated by the invention, the mixer may comprise an oscillator adapted to oscillate at a frequency corresponding to the higher in frequency of the signals to be mixed. This oscillator may be of a form which is adapted to be amplitude-modulated in response to a frequency-modulated signal corresponding to the lower in frequency of the input signals to be mixed. If there exist certain conditions, presently to be specified, there will appear, in the output or tank circuit of the oscillator, the spectrum hereinbefore referred to, in which the fundamental or carrier component is of the frequency of the higher of the input signals and is substantially fixed in frequency, while the sideband components have mean frequencies equal to the sums and differences of the higher input frequency and integral multiples of the lower input frequency, and vary in frequency in accordance with the modulation of the lower input frequency. The principal condition precedent to the production of this desired spectrum is that the oscillations generated by the oscillator, when it is modulated, must be phase-cohered—that is, the phase of the oscillations at any instant must be governed by the phase of oscillations that existed at any previous instant. This condition is readily obtained if the amplitude of oscillations is never permitted to decay below a certain level which is dependent upon various factors including, for example, the noise level in the system and the magnitudes of spurious signals existing therein.

When such an arrangement is employed, the means used to lock a particular sideband component and maintain its frequency substantially invariant may, for example, comprise an auxiliary tuned circuit or tank, of relatively high Q compared to that of the oscillator, tuned to the mean frequency of the sideband to be locked, and coupled to the oscillator tank circuit. The effect of this auxiliary tank is to overcome, substantially, variations in the frequency of the particular sideband component, thereby causing the fundamental or carrier component of the spectrum to assume these variations.

Alternatively, locking may be effected by means of a separate oscillator, oscillating at the mean frequency of the sideband component to be locked and coupled to the oscillator tank circuit so as to supply energy thereto.

That the method is particularly well adapted for effecting modulation of the output energy from a cavity magnetron oscillator will, in view of the foregoing, be readily apparent. Thus, to the cathode of the magnetron there may be supplied a frequency-modulated carrier wave signal whose mean frequency is lower than the frequency of oscillation of the magnetron. The application of this signal in this manner will produce effective variations in the conductance of the magnetron oscillator circuit. The amplitude of the signal should be such, and it should be applied in such manner, that the oscillations produced in the magnetron output cavity will be phase-cohered, in the sense previously defined. It has been determined that this condition can be satisfied even when the magnetron is operated

class C at a relatively low duty cycle. The output will then contain a component of relatively large magnitude, substantially invariant in frequency and having a frequency equal to a normal frequency of oscillation of the magnetron, together with sideband components whose mean frequencies are equal to the sums and differences of the magnetron oscillation frequency and integral multiples of the mean frequency of the modulating signal, and which vary in accordance with the variations in frequency of the latter signal. However, there are also provided appropriate means, in the form of the auxiliary tank circuit or oscillator hereinbefore mentioned, coupled to the magnetron cavity so as to maintain substantially fixed the frequency of one of the sideband components, whereby the frequency of the fundamental or carrier component is caused to vary in accordance with the modulating signal (i. e. according to the frequency variation of the signal applied to the cathode of the magnetron to drive it).

Not only is the method adapted for use with magnetrons of the more conventional type in the manner above set forth, but it is usable to advantage with the more recently developed electron deviator types, hereinbefore referred to, in which the frequency of oscillation is deviable throughout comparatively wide ranges through the agency of electron beams of controllable intensity flowing in the cavities of the magnetron. In utilizing a magnetron of the electron deviator type in accordance with the invention, the input, frequency-modulated, carrier wave signal, instead of being applied to anode-modulate the magnetron (and thereby produce modulation of the conductance of the oscillator circuit) as in the case above described, is applied to the grid or grids controlling the intensities of the electron beams in the magnetron cavities. Thus the capacitance of the equivalent oscillator circuit is modulated, the frequency of oscillation of the magnetron is deviated in response to the frequency-modulated input signal, and there is produced an output spectrum comprising at least some components whose frequencies vary in response to the variations in frequency of the input signal. Locking of one of these components is effected by either of the aforementioned expedients of using an auxiliary tank tuned to the mean sideband frequency, or using a separate c-w oscillator supplying energy to a cavity of the magnetron at the mean frequency of the sideband desired to be locked.

This last described method of applying the invention illustrates feature thereof which is of considerable significance—namely, that the oscillator to be heterodyne-modulated need not necessarily be amplitude-modulated by the lower frequency intelligence-modulated input signal. On the contrary, the oscillator may be modulated, in response to this signal, in amplitude, frequency or phase, or in any convenient combination of these three. Any one, or combination, of these methods of modulation will result in the production of an output spectrum comprising a plurality of sideband components, at least some of which will vary in frequency in response to variations in the frequency of the input signal. Accordingly the frequency of one of these normally variable components may be locked by one of the methods aforementioned, and the frequency of another of the components will thereby be caused to vary in response to the frequency modulation

of the input signal, and can be employed as useful, frequency-modulated output.

Thus it will be apparent that, although the method is by no means confined, in its application, to the magnetron type of oscillator, it is, nevertheless, a very important feature of the invention that it provides a method of utilizing a magnetron for purposes for which, heretofore, it has not been considered to be suited—namely, the achievement of highly linear and efficient modulation of large quantities of power in the super-high frequency or microwave range.

Accordingly, in its broader aspect, the invention may be regarded as comprising a modulating system consisting of: a source of a signal of predetermined frequency, a source of a second signal of modulated frequency, means for mixing said first and second signals to yield a third signal, said third signal comprising a plurality of frequency components, at least one of which tends to be frequency-modulated in some degree in accordance with the frequency-modulation of said second signal, means for substantially reducing the tendency toward variation in the frequency of said one component, whereby there is imparted to another of said components frequency variations according in some degree to the modulation of said second signal, and means for deriving an output signal which varies in frequency in accordance with the frequency variations of said other component.

The method of the invention, the manner in which it may be practiced, and the details of construction and operation of representative embodiments in accordance therewith, will be more fully appreciated from a consideration of the following specification together with the accompanying drawings, in which:

Figure 1 is a basic equivalent circuit of a heterodyne modulated oscillator according to the invention.

Figure 2 is the equivalent circuit of a typical practical embodiment of the invention as illustrated in Figure 3.

Figure 3 illustrates, partially schematically and partially diagrammatically, one embodiment of a heterodyne modulated oscillator according to the invention in which locking of a particular sideband component in the output from a magnetron oscillator is effected by means of an auxiliary cavity resonator coupled to the magnetron output.

Figure 4 is a fragmentary sectional perspective view taken along the line 4—4 of Figure 3.

Figure 5 is the equivalent circuit of a constant impedance filter comprising a portion of the embodiment of Figure 3.

Figure 6 illustrates an arrangement for compensating for incomplete locking of the sideband component in the output of a heterodyne frequency-modulated oscillator, which may result when the magnitude of the sideband component is made relatively small compared to the fundamental component in order to secure unusually high efficiency.

Figure 7 illustrates an embodiment of a heterodyne modulated oscillator according to the invention, in which locking of a particular sideband component in the output of a magnetron oscillator is effected by injection of a continuous wave signal from a separate source into a cavity of the magnetron, and

Figure 8 illustrates an embodiment of the invention incorporating an intermediate frequency

amplifier for supplying the input modulated carrier wave signal to the oscillator which is to be heterodyne modulated in response thereto, and adapted to predistort the signal thus supplied in a manner to compensate for a tendency which may exist for the output signal from the oscillator to include variations which are a function of the rate of change with time of the frequency of the input signal thereto.

Referring now to Figure 1, which illustrates the equivalent circuit of an elementary form of a heterodyne-frequency-modulator circuit employing a magnetron oscillator in accordance with the invention, the magnetron oscillator itself is represented by the tuned circuit 1, having losses, represented by shunt conductance G_{10} , and shunted by a variable conductance 3 to simulate the variable conductance of the magnetron oscillator, which must be capable of assuming at least negative values. The tank circuit 1 of the oscillator is coupled, through a suitable coupling admittance 4, to an auxiliary parallel resonant circuit 5 tuned to the frequency of the sideband, in the output of the conductance modulated oscillator, which it is desired to hold fixed. Modulation of the oscillator is effected by varying conductance 3 in response to a frequency-modulated input signal. The carrier and sideband components hereinbefore referred to, as determined by the characteristics of the input signal and the frequency of oscillation of the magnetron, appear across the magnetron tank circuit 1.

Practically, however, the circuit of a modulator in accordance with the invention may not be as simple as that represented by the equivalent circuit of Figure 1. Rather the equivalent circuit of a practical heterodyne frequency modulator may be as represented in Figure 2. Here, as in Figure 1, the magnetron is represented by a parallel tuned circuit 11 shunted by a variable conductance 12, the magnitude of which varies in accordance with the instantaneous value of the modulated input signal. The oscillator tank circuit is coupled, by means of a transmission line section 13, to a signal utilization circuit 14 having an impedance Z_L . As illustrated, the left-hand end of this transmission line section may be inductively coupled to the oscillator tank circuit. At a point interjacent the ends of transmission line section 13, there may be inductively coupled thereto, the auxiliary tank circuit 15. If, as illustrated in the figure, the effective electrical length of the portion of transmission line section 13, between the coupling to oscillator tank 11 and the point of coupling between auxiliary tank 15 and the transmission line section, is an odd number of half-wave lengths, at a frequency approximating that of the oscillations, then this portion of the transmission line section may be omitted completely, and the equivalent circuit of Figure 2 is reduced to a circuit which is very similar in form to that of Figure 1. Attention is here invited to this equivalence inasmuch as it will be of assistance later in explaining the operation of an embodiment of the invention.

The embodiment of the invention illustrated in Figure 3 may be represented by an equivalent circuit corresponding substantially to that of Figure 2. In Figure 3, the output of a cavity magnetron oscillator 21 is supplied through a length of coaxial transmission line 22, of suitable characteristics, to one end of a waveguide section 23. The coupling between transmission line section

22 and waveguide 23 may be capacitive and is effected in conventional manner by permitting the internal conductor 22a of line section 22 to extend approximately halfway into waveguide 23 in a direction normal to the larger cross-sectional dimension of the guide, as illustrated. At its other end, the waveguide section is provided with a Y-junction 24 which feeds separate waveguide sections 25 and 27 having cross-sectional dimensions which are preferably almost equal to those of section 23. One of these sections, 25, is terminated in an antenna or other useful load 26, while the other section, 27, is terminated in a dummy load 28.

Coupled to waveguide section 23, at a point interjacent its juncture with transmission line section 22 and its termination in Y-junction 24, is an auxiliary cavity resonator 29, tunable by means of tuning screw 29a. The degree of coupling is controllable through the agency of an adjustable iris 30 formed by slideable members 31 and 32, adjustable through the cooperation of screws 33 and 34, as shown in detail in the fragmentary sectional perspective view of Figure 4. In the embodiment illustrated, the coupling is magnetic by reason of the arrangement of the resonator with reference to the waveguide so that the magnetic lines of force in both resonator and waveguide, in the vicinity of the iris, are essentially parallel (TE_{1,0} mode of propagation in the waveguide). However it is to be understood that similar results would be obtained using capacitive coupling. The length of that portion of waveguide section 23, between its coupling to resonator 29 and its juncture with transmission line section 22, is adjustable by means of a "line-stretcher" 35. This is formed conventionally by providing elongated slits 35a in opposite walls of the waveguide to permit small variations in the spacing of the other opposing walls of the guide to be effected by turning screw 35d in clamp member 35c. Similarly, that portion of waveguide 23 between the coupling to resonator 29 and its termination in Y-junction 24, is adjustable in length by means of a similar "line-stretcher" 36. Immediately adjacent the Y-junction there is also provided a tuning screw 41 for the purpose of modifying the voltage standing wave ratio in the waveguide section, for reasons which will be explained hereinafter.

Waveguide sections 25 and 27 are provided, respectively, with branch portions 37 and 38, which are separately variable in effective length through the agencies of slideable pistons 39 and 40. Each of these branch sections is preferably displaced electrically, from the effective center of Y-junction 24 an integral number of half wavelengths at the fundamental frequency of magnetron oscillator 21. The effective electrical length of section 37 is adjusted to be an integral number of half wavelengths at the magnetron frequency; while that of section 38 is made substantially equal to an odd number of quarter wavelengths at the same frequency. As a result of these adjustments waveguide sections 25 and 27, and their associated sections 37 and 38, will cooperate with dummy load 28, when the impedance of the latter is made equal to that of useful load 26, to provide, in effect, a bandpass filter interposed between Y-junction 24 and antenna or useful load 26. The filter thus formed will present a substantially constant input impedance at Y-junction 24 and may be adjusted so as to transmit to the antenna or useful load the fundamental frequency component in the output from magnetron oscillator

21, to which will have been imparted variations substantially corresponding to those of the frequency-modulated I.-F. input signal, as will be explained hereinafter. It should also be adjusted to transmit neither the locked nor the other sideband components. The equivalent circuit of the filter is illustrated in Figure 5. In this circuit, resistor 55 represents the useful, and resistor 56, the dummy load, both having impedances Z_0 . Series tuned circuit 57, of impedance Z_2 , represents the waveguide section 37 in the embodiment of Figure 3, while parallel tuned circuit 58 represents waveguide section 40 of Figure 3 and has an impedance Z_1 . The product of Z_1 and Z_2 is made equal to Z_0^2 , whereupon the impedance looking into the network is equal to Z_0 , the load impedance.

Magnetron 21, which may be a conventional c-w magnetron operating in the S, X or K band, is driven by a suitable driver tube, which, in this instance, is pentode 42. The plate of tube 42 is coupled through condenser 43 to the cathode of the magnetron, and the cathode leads supplying heater power thereto may include a bifilar winding 44 which acts as an R.-F. choke at the frequencies comprising the signal supplied to the magnetron to drive it. Also, there may be included a resistor 45, connected between the magnetron cathode and ground, which cooperates with the inherent capacitance of the cathode to provide the necessary bandwidth in the coupling circuit between the driver tube 42 and magnetron 21.

The driving signal, which may be a frequency-modulated intermediate frequency carrier derived from the output of an intermediate frequency amplifier (not shown) is supplied through coupling condenser 47 to the control grid of pentode 42. From theoretical considerations it might be thought that most efficient operation of the magnetron would be obtained if the magnitude of the driving signal were adjusted so as to produce class C operation of the magnetron (i. e. so that oscillations build up in the magnetron during only a relatively small portion of each I.-F. cycle). Actually this may not be the case because of the relatively large amount of power which is normally required to drive the magnetron class C. Accordingly, for the achievement of optimum over-all efficiency, it may be preferable to adjust the magnitude of the I.-F. input signal applied to the control grid of tube 42 so as to cause less violent modulation of the magnetron (i. e. so that the magnetron oscillates during a relatively large portion of each I.-F. cycle).

The frequency-modulated input signal applied to drive the magnetron will cause oscillations to build up in the magnetron intermittently at a rate which varies in accordance with the frequency modulation of the driving signal. As a result of this mode of operation, there will exist, in the magnetron output cavity, signal frequency components corresponding to the normal frequency of oscillation of the magnetron, as well as sideband modulation components corresponding to the sums and differences of the normal frequency of oscillation of the magnetron and integral multiples of the mean or carrier frequency of the frequency-modulated driving signal. As already mentioned heretofore, the normal tendency will be for the fundamental or carrier frequency (corresponding to the natural frequency of oscillation of the magnetron) to remain substantially constant, while the frequency of the sideband components vary in ac-

cordance with the frequency modulation of the driving signal. However, in the arrangement illustrated in Figure 3, owing to the presence of auxiliary cavity resonator 29 coupled to the magnetron output cavity through the agency of waveguide 23 and transmission line section 22 and tuned to the mean frequency of one of the sideband components, a substantial force will be exerted tending to overcome the variation in frequency of that particular sideband component and tending at the same time to produce similar variations in the frequency of the fundamental or carrier component of the magnetron output. It has been determined that such locking of a sideband component will take place where the effective electrical length of the coupling circuit between the output cavity of magnetron 21 and cavity 29, comprising transmission line section 22 and the left-hand portion of waveguide section 23, is equal to an integral number of half wavelengths. Actually it appears that this is not a critical requirement and that this length may be varied considerably without adversely affecting the ability of cavity resonator 29 to lock the selected sideband component in the output from magnetron 21.

The effectiveness of the auxiliary cavity resonator in locking the selected sideband in the output spectrum of a heterodyne frequency-modulated oscillator is of primary importance in determining the efficiency of operation according to the method of the invention. This effectiveness is controlled by several factors in addition to the one just mentioned. To appreciate more fully the nature of these factors and their effect, it will be helpful to refer again to the equivalent circuit of Figure 1.

Before proceeding with a discussion of the several factors which influence the effectiveness of locking, it will be desirable to define certain terms presently to be used in discussing the equivalent circuit of Figure 1 as follows:

Tuned circuit 1 will be referred to as the primary.

Tuned circuit 5 will be referred to as the secondary.

"Loaded primary" refers to the condition of tuned circuit 1 when points E and F are short-circuited.

"Loaded secondary" refers to the condition of tuned circuit 5 when points D and F are short-circuited.

"Unloaded primary" refers to that portion of tuned circuit 1 comprising L_{10} , C_{10} and the portion of G_{10} which represents unavoidable losses of the circuit (i. e. G_{10} is to be regarded as comprising the inherent conductance of the tuned circuit plus any conductance which may be introduced incident to extracting power or modifying bandwidth).

"Unloaded secondary" refers to the condition of tuned circuit 5 when the resistive component of coupling admittance Y_{12} is infinite.

ω_{11} =resonant frequency of loaded primary,

ω_{22} =resonant frequency of loaded secondary,

γ_{11} =half bandwidth of loaded primary,

γ_{22} =half bandwidth of loaded secondary,

ω_m =modulating frequency,

Q_{10} = Q of unloaded primary,

Q_{11} = Q of loaded primary,

Q_{20} = Q of unloaded secondary, and

Q_{22} = Q of loaded secondary.

Q , in accordance with conventional notation, designates the ratio of reactance to resistance of a particular circuit.

There follows an enumeration and discussion of each of the factors principally affecting the effectiveness of locking.

(1) *Q of the loaded primary*

For best locking, the *Q* of the loaded primary should be as low as is consistent with the requirement to sustain oscillations.

(2) *Q of the loaded secondary*

This should be as high as possible, but is limited by the fact that the loaded *Q* cannot exceed the unloaded *Q*, which, in turn, is inherently limited. It is also to be noted that the *Q* of the loaded secondary will be reduced depending upon the magnitude of the conductive component of the coupling admittance. As will presently become apparent it is desirable that there be a conductive component. In determining the magnitude of this component, its effect in lowering the *Q* of the secondary must, of course, be considered.

(3) *Phase and magnitude of the coupling admittance Y_{12} between primary and secondary*

It can be demonstrated, if certain justifiable assumptions are made, that, for best locking, the phase angle of the coupling admittance between primary and secondary is given by the expression:

$$\phi = \tan^{-1} \frac{\omega_{22} - \omega_{11}}{\gamma_{11} - \gamma_{22}} \quad (1)$$

Although this expression is derived from a consideration of an oscillator modulated class C at a relatively low duty cycle, experiment shows that good results are obtained by following it in cases where the modulation is less violent and where the duty cycle is relatively high. The phase angle ϕ may be controlled by appropriate selection of the magnitude of the conductive and susceptive components of the coupling admittance. However, as mentioned in (2) above, the conductive component cannot be increased beyond a certain value without unduly loading the secondary. In the circuit according to Figure 3, the magnitude and phase of the effective coupling admittance between the output cavity of magnetron 21 and auxiliary cavity 29 is adjustable by means of "line stretcher" 36 and tuning screw 41. The former, as has already been mentioned, is effective to vary the electrical length of that portion of waveguide section 23 between cavity resonator 29 and Y-junction 24, while the latter is adapted to control the conditions of impedance mismatch in the vicinity of the Y-junction.

(4) *Impedance level of the secondary*

If the L/C ratio of the secondary were zero, the secondary, even at resonance, would present a short circuit between points E and F in Figure 1 and hence would exert no influence on the oscillator. If, on the other hand, the L/C ratio were very large, the secondary would be unduly loaded and would be incapable of effectively locking a sideband. It has been determined that, when the phase angle of the coupling admittance is that specified by Equation 1, the impedance level is optimum for sideband locking when the following condition is satisfied:

$$\frac{Q_{20}}{Q_{22}} = 1 + \frac{Q_{10}}{Q_{11}} \quad (2)$$

As in the case of expression (1) for the phase angle of the coupling admittance, expression (2) is derived from consideration of an oscillator modulated class C at a relatively low duty cycle, but it has been ascertained that it serves as a

satisfactory guide in other cases as well. Adjustment of the impedance level to satisfy this condition is made in the arrangement according to Figure 3 by variation of the magnetic coupling between waveguide section 23 and cavity resonator 29 through variable iris coupling 39.

(5) *Frequency and bandwidth of modulating signal*

10 The mean frequency of the frequency-modulated input signal which drives the oscillator determines the spacing of the frequency components in the spectrum of the output of the modulated oscillator, and hence the difference between the resonant frequencies of the primary and secondary. In general, the lower is this mean frequency, the better will be the locking of a particular sideband. If, however, a wideband intelligence is to be transmitted, the modulating frequency must be relatively high to permit satisfactory design of amplifiers through which the modulating signal must pass before being used to drive the oscillator. Moreover the modulating frequency cannot be limited to too low a value without unduly restricting the usefulness of the system as a frequency converter. In typical embodiments, satisfactory locking will obtain if the modulating frequency is made of the order of the half-bandwidth of the loaded primary.

15 20 25 30 35 40 45 50

At the same time, the bandwidth of the modulating signal cannot be increased unduly without increasing distortion of the output signal. It is preferable, for example, that it not exceed one-tenth the half-bandwidth of the loaded primary. In the case of a magnetron, the half-bandwidth increases as the frequency of operation of the magnetron increases. Hence, if the input signal comprises a wide band of frequency components, it is preferable to use a magnetron adapted for operation at a higher frequency than if only a narrow band input signal is involved. Thus, for example, if television signals are involved, satisfactory results will more readily be obtained using an X-band magnetron than by using an S-band magnetron. However, it should be understood that even an S-band magnetron could, under certain circumstances, be made to operate satisfactorily in this application if pains are taken to insure suitably high *Q* of the secondary circuit.

55 60 65 70 75

It will be apparent that, in order for a heterodyne frequency-modulated oscillator to operate at high efficiency, it will be desirable to have the carrier frequency component of the output signal spectrum as large as possible, while minimizing the magnitudes of the sideband components, including the sideband to be locked. However, it appears, as corollary to the above criteria for optimum locking of a selected sideband, that satisfactory locking cannot ordinarily be achieved if the power represented by the sideband to be locked is made unduly small compared to the power represented by the carrier component. If the magnitude of the selected sideband component is reduced beyond a certain point it will be impossible, by either of the aforementioned methods, to hold it essentially fixed in frequency in order that its variations may be imparted to the carrier component. The greater the reduction beyond this point of the power represented by the sideband component, the more will the frequency of the component tend to vary in accordance with variations in frequency of the modulated intermediate frequency input signal, and the less will these variations tend to be imparted to the

carrier component of the output signal. This result may be regarded as a form of distortion in the modulated carrier wave signal produced. If the variations in frequency of the "locked" sideband component are linear with respect to the variations in frequency of the modulated input signal, this distortion will not be objectionable, but will amount merely to a gain or loss in deviation of the frequency-modulated output signal compared to that of the frequency-modulated input signal. A loss in deviation might prove to be of some disadvantage in the case of a high frequency relay chain comprising a plurality of relay stations each employing heterodyne frequency-modulation. After transmission through a number of such stations, the intelligence contained in the original frequency-modulated signal would, to a large extent, be dissipated unless some special steps were taken to preserve it.

It has been discovered that, in a heterodyne frequency modulation system, the efficiency can be raised appreciably by delegating a considerably greater amount of power to the carrier frequency component of the output signal, while correspondingly reducing the amount of power in the sideband component to be locked, and at the same time avoiding the disadvantages of nonlinear distortion and of loss in deviation. To this end, it is feasible to compare the deviation of the carrier component in the output from a heterodyne frequency modulator with the deviation of the frequency-modulated input signal which produces it. From this comparison it is possible to derive a control signal proportional to the difference in deviation between the output carrier and the modulated input signal. This signal, in turn, may be used to modify the operation of the heterodyne frequency-modulated oscillator in a manner to compensate for the failure of the system to maintain the frequency of the "locked" sideband component essentially fixed. For example, the control signal may be applied to vary the normal frequency of oscillation of the oscillator. In the case of a magnetron, for example, this might be effected by using the control signal to vary the anode voltage of the magnetron, or by applying the control signal to the frequency control element of an electrically-deviated magnetron of the sort described in "Proceedings of the Institute of Radio Engineers" for July, 1947, page 657. Alternatively, compensation of the output signal from the heterodyne frequency-modulated oscillator might be achieved by varying the tuning of the auxiliary tank circuit in an arrangement such as the one shown in Figure 3. For this purpose it would likewise be feasible to utilize the electronic method of varying the tuning of a cavity resonator described in the aforementioned issue of "Proceedings of the Institute of Radio Engineers," page 644 et seq.

A block diagram of a typical arrangement for controlling the frequency of oscillation of a heterodyne frequency-modulated oscillator, in accordance with the method above outlined, so as to minimize the difference in frequency deviation between the modulated input signal to the oscillator and the modulated output therefrom, is illustrated in Figure 6. In this arrangement a portion of the output from heterodyne frequency-modulated oscillator 60 is supplied to mixer 61. The mixer is also supplied with a suitable signal from local oscillator 62 and is adapted to convert the portion of the modulated output from heterodyne frequency-modulated oscillator 60 to

a lower carrier frequency, which is preferably substantially the same as the carrier frequency of the modulated input signal to the heterodyne frequency-modulated oscillator. The heterodyne output from mixer 61 is supplied to a discriminator circuit 63, which is tuned to the carrier frequency of the output signal from the mixer, and which is adapted to produce an output which varies in accordance with the deviation of the signal thus supplied to it. Another similarly tuned discriminator 64 is supplied with a portion of the frequency-modulated I.-F. input signal supplied to heterodyne frequency-modulated oscillator 60 and is adapted to produce an output whose magnitude varies in accordance with the deviation of the frequency-modulated I.-F. input signal. The outputs from discriminators 63 and 64 are compared in a conventional comparator 65, which is adapted to develop a control signal proportional to any difference in their magnitudes. This control signal is supplied through connection 66 to control heterodyne frequency-modulated oscillator 60, by any of the methods above referred to, so as to compensate for the difference in deviation between the input signal thereto and the output signal therefrom.

It will be noted that when the deviation of the modulated output signal from heterodyne frequency-modulated oscillator 60 is the same as the deviation of the modulated I.-F. input signal supplied thereto, the outputs from discriminators 63 and 64 will be the same and no control signal will be produced by comparator 65. However, if there is a difference in deviation between the input signals to heterodyne frequency-modulated oscillator 60, and the output signals therefrom, the outputs from discriminators 63 and 64 will differ and a control signal will be developed by comparator 65 which will tend to correct this condition. It will also be noted that the provision of mixer 61, for converting the modulated output from heterodyne frequency-modulated oscillator 60 to a lower carrier frequency for supply to discriminator 63, permits the use of discriminators 63 and 64 tuned to the same center frequency. Thus, there is avoided the possibility of unbalance in the system which might result from the use of discriminators tuned to different center frequencies.

It will of course be understood that the arrangement just described with reference to Fig. 6 represents but one of the possible ones for modifying the operation of the heterodyne frequency-modulator in response to the output therefrom so as to counteract for the failure of the modulator to maintain the frequency of the locked sideband component substantially fixed. Other equally effective arrangements for achieving this result will occur to those skilled in the art for achieving these results in accordance with the general principles as above set forth. These improvements, including the embodiment just described, are the subject of a separate copending application Serial No. 61,979, filed November 26, 1949, by Stephen W. Moulton for an Electrical System, which contains claims directed to them.

In Figure 7 is illustrated, schematically, the circuit of a heterodyne frequency-modulated oscillator in which locking of the selected sideband is achieved by injecting, into the oscillator tank circuit, a continuous wave signal of frequency substantially equal to the mean frequency of the sideband to be locked. In this circuit arrangement a magnetron 70 is driven, in the same manner as

hereinbefore described with reference to Figure 3, by a frequency-modulated I.-F. input signal supplied to the cathode of the magnetron through a driving circuit including tube 71, and which otherwise may be identical to that illustrated in Figure 3 for driving magnetron 24. A locking signal, of frequency equal to the mean frequency of the sideband to be locked in the output from magnetron 70, is supplied by a suitable c-w oscillator 72, which may be of conventional construction, through a buffer amplifier 73 and transmission line section 74, and is injected into a cavity of the magnetron through the agency of coupling loop 75. Oscillator 72 should be capable of supplying sufficient power to insure locking of the desired sideband, the amount of power required under any given set of circumstances being readily determinable by experiment. Buffer amplifier 73 should be designed to provide adequate isolation to prevent oscillations in the magnetron from "pulling" the frequency of oscillator 72. The criteria for satisfactory locking hereinbefore mentioned are equally applicable in this instance, excepting, of course, the ones relating to the characteristics of the auxiliary tuned circuit, which is not used in this embodiment. In the operation of the present circuit, when satisfactory locking is effected, the fundamental or carrier frequency in the output of magnetron 70 will be caused to vary in frequency in substantially the same manner as the intermediate frequency input signal. Useful power output represented by this component is conveniently derivable from a cavity of the magnetron by means of a suitable coupling loop 76 and transmission line section 77.

It has already been observed that, under certain circumstances, in a heterodyne frequency modulation system according to the invention, there may be a tendency for a form of distortion to appear in the modulated output signal. As was mentioned, this is particularly likely to be the case where the amount of power in the fundamental or carrier frequency component is made large, compared to that in the locked sideband component, in order to secure greater efficiency of operation. A method of and means for avoiding or minimizing this distortion, while maintaining high efficiency, has already been discussed. Under certain circumstances a further refinement in the system, directed toward the elimination or minimization of another form of distortion, may be desirable. This further refinement will now be discussed.

In a heterodyne frequency-modulation system, if the variations in the frequency-modulated input signal occur relatively slowly, and if the locked sideband is maintained substantially fixed in frequency, the variations in frequency of the output signal will be almost directly proportional to the variations in frequency of the modulated input signal. However, as the rate of variation of the frequency of the modulated input signal increases, this proportionality will tend to be destroyed. More particularly, it is found that the variations in the output signal will no longer be proportional solely to the variations in the input signal, but will be dependent also upon the rate at which the input signal varies. In other words, the variations in the output signal will tend to become a function of the rate of change with time of the modulated input signal. This constitutes a form of distortion in the output signal, the nature of which can best be appreciated by considering the frequency-modulated input signal as consisting of a fixed frequency component (i. e. the nominal I.-F. input frequency) plus a

variable component representative of the modulation. Similarly the frequency-modulated output signal may be regarded as consisting of a fixed component (i. e. the carrier frequency) plus a variable component representative of the modulation. It is then found that there exists an expression relating the variable component of the frequency-modulated output signal to the variable component of the frequency-modulated input signal, the instantaneous frequency of the input signal and the rate of change thereof with time. In the case where the first lower sideband is locked, this expression is:

$$\omega_{\text{out}} = \omega_{\text{in}} - \frac{\gamma_{11}}{\gamma_{11}^2 + (\omega_m - \mu)^2} \cdot \frac{d\omega_m}{dt} \quad (3)$$

in which ω_{out} is the variable component of the frequency-modulated output signal, ω_m is the variable component of the frequency-modulated input signal, γ_{11} is the half bandwidth of the loaded primary in the equivalent circuit of Figure 1, μ is the magnitude of the displacement of the locked sideband from the resonant frequency of the primary, and ω_m is the instantaneous frequency of the frequency-modulated input signal which varies with time. The latter term in this expression represents the distortion component in the frequency-modulated output signal which, as above mentioned, is a function both of the instantaneous value of the frequency-modulated input signal and the first derivative thereof with respect to time. It will be apparent that the distortion term increases with an increase in the rate of variation of the frequency-modulated input signal as well as with the reduction in the difference between ω_m and μ .

It has been determined that, at least under certain circumstances, this form of distortion can be eliminated or substantially reduced through the expedient of predistorting the frequency-modulated input signal before it is applied to modulate the oscillator. Thus, it has been determined that, in a heterodyne modulated oscillator operated Class C at a relatively low duty cycle, and where the first lower sideband in the output from the oscillator is locked, the necessary predistortion can be effected, to achieve complete compensation, by passing the modulated input signal through a frequency discriminatory passive transducer having a transfer impedance characteristic given by the expression:

$$Z = K[\gamma_{11} + j(\omega_m - \mu)] \quad (4)$$

where K is an arbitrary real constant, and γ_{11} , ω_m and μ are as hereinbefore defined with reference to Equation 3.

Similarly, in the case in which the first upper sideband is locked, the desired compensation may be accomplished completely by passing the frequency-modulated input signal through a passive transducer whose transfer impedance characteristic is given by the expression:

$$Z = K[\gamma_{11} - j(\omega_m - \mu)] \quad (5)$$

where the symbols used are of the same significance as in the previous expression.

In practice, the predistorting transducer may comprise a portion of the amplifier through which the intermediate frequency signal is supplied to drive the oscillator which is heterodyne-modulated. To this end, the coupling network between successive amplifier stages may be designed in a manner to yield the desired distortion. For example, where the first lower sideband is locked, it has been determined that, if the coupling network is made to consist of a sim-

ple series tuned circuit, with dissipation, as in the arrangement according to Figure 8, a high degree of compensation will result even though this relatively simple form of coupling network provides but an approximation to the transfer impedance characteristic as prescribed by Equation 4. The attainment of such results is, of course, predicated upon the appropriate selection of the values of the coupling network parameters, but, as will presently become apparent, these values are not very critical.

In the coupling network according to Figure 8, the impedance Z_{AB} between points A and B is given, in accordance with well-known principles of network theory, by the expression:

$$Z_{AB} = K' \frac{[\gamma + j(\omega - \omega_r)][\gamma + j(\omega + \omega_r)]}{a\gamma + j\omega} \quad (6)$$

where:

$$\gamma = \frac{CR_1R_2 + L}{2LCR_2}$$

$$\omega_r = \sqrt{\frac{R_1 + R_2}{LCR_2}} - \gamma^2 \quad (7)$$

$$a = \frac{2L}{L + CR_1R_2}$$

and

$$k' = L$$

The form of this expression is such, it will be observed, that the impedance defined by it is characterized in having two complex conjugate zeroes and a real pole.

If it is assumed that $\omega_r = \mu$, the magnitude of the displacement of the locked lower sideband from the resonant frequency of the primary, in Equation 4; and that $\gamma = \gamma_{11}$, the half-bandwidth of the loaded primary, then, if the bandwidth of the intermediate frequency is not unduly wide, distortion in the output of the heterodyne modulated oscillator will become substantially nonexistent if the value of the parameter a in Equation 6 is selected so as to satisfy the relation:

$$1 + \left(\frac{\omega_{IF} + \mu}{\gamma_{11}} \right)^2 = a + \frac{\omega_{IF}^2}{a\gamma_{11}^2} \quad (8)$$

where ω_{IF} is the mean intermediate frequency.

If, for example, $\omega_{IF} + \mu = \gamma_{11}$, the value of a will be approximately 0.209. This is within the range of values of a which are susceptible of physical realization, since $a=0$ when $R_2=\infty$ and $a=2$ when $R_1=0$.

Once the values of the parameters γ , ω_r and a have been ascertained for any specific case, it is readily possible, from Equations 7 to determine the values of L , C , R_1 , and R_2 in the coupling network according to Figure 8. Before doing this, however, it is first necessary to specify the impedance level of the coupling network between points A and B. For practical purposes, this level is limited by the inherent capacitance with respect to ground of amplifier tube 80 and the grid-to-ground capacitance of tube 81.

For example, if tubes 80 and 81 are type 6AK6 and are operated at an intermediate frequency of 50 megacycles, values of the circuit constants which will satisfy Equations 6 and provide a suitable impedance level are:

$$L = 4.63 \times 10^{-8} \text{ henries}$$

$$C = 135 \mu\mu\text{-farads}$$

$$R_1 = 26.2 \text{ ohms}$$

$$R_2 = 112.3 \text{ ohms}$$

To provide adequate gain, coupling condenser C_c should be of the order of magnitude of $50 \mu\mu \text{ fd}$.

The method and means just discussed, for pre-distorting the input signal to a heterodyne frequency-modulator in a manner to reduce the tendency of the output signal therefrom to contain frequency variations which are a function of the rate of change with time of the frequency of the input signal, are claimed in copending application of Stephen W. Moulton, Serial No. 65,301, filed December 12, 1948, now U. S. Patent No. 2,529,736 issued November 14, 1950, for an Electrical System.

I claim:

1. In a modulating system, an oscillator having a tank circuit, means responsive to a signal of modulated frequency for controlling said oscillator in a manner to produce in said tank circuit a plurality of frequency components, at least one of which tends to be frequency-modulated in some degree in substantial accordance with the modulation of said signal and at least another of which is of substantially greater magnitude than said one component, a resonant circuit coupled to said tank circuit, said resonant circuit being tuned to substantially the mean frequency of said one component and being operative to reduce the tendency of said one component to be frequency-modulated and to impart to said other component frequency variations according in some degree to the modulation of said one component which would have existed in the absence of said reduction, and means for deriving from said oscillator an output signal which varies in frequency in accordance with the frequency variations of said other component.

2. In a modulating system, an oscillator having a tank circuit, means responsive to a signal of modulated frequency for controlling said oscillator in a manner to produce in said tank circuit fundamental and sideband frequency components, said fundamental component being of appreciably greater magnitude than said sideband components and at least one of said sideband components having a tendency to be frequency-modulated in some degree in substantial accordance with the modulation of said signal, a resonant circuit coupled to said tank circuit, said resonant circuit being tuned to substantially the mean frequency of said one sideband component and being operative to reduce the tendency of said one component to be frequency-modulated and to impart to said fundamental component frequency variations according in some degree to the modulation of said one component which would have existed in the absence of said reduction, and means for deriving from said tank circuit an output signal which varies in frequency in accordance with frequency variations of said fundamental component.

3. In a modulating system, an oscillator having a tank circuit, means responsive to a signal of modulated frequency for controlling said oscillator in a manner to produce in said tank circuit a plurality of signal frequency components, at least one of which tends to be frequency-modulated in some degree in substantial accordance with the modulation of said signal, an auxiliary source of energy of a frequency closely approximating the mean frequency of said one component, means for supplying energy from said source to said tank circuit to reduce the tendency of said one component to be frequency-modulated and to impart to another of said com-

ponents frequency variations according in some degree to the modulation of said one component which would have existed in the absence of said reduction, and means for deriving from said tank circuit an output signal which varies in frequency in accordance with frequency variations of said other component.

4. In a modulating system, an oscillator, a signal utilization device, a waveguide coupling said oscillator to said utilization device and adapted to supply signals generated by said oscillator to said utilization device, means responsive to a signal of modulated frequency for controlling said oscillator in a manner to produce therein a plurality of signal frequency components, at least one of which tends to be frequency-modulated in some degree in substantial accordance with the modulation of said first-named signal, and a cavity resonator coupled to said waveguide at a point interjacent said oscillator and said utilization device for reducing the tendency of said one component to be frequency-modulated and for imparting to another of said components frequency variations according in some degree to the modulation of said one component which would have existed in the absence of said reduction, said resonator being tuned to substantially the mean frequency of said one component and having a Q substantially greater than the Q of said tank circuit, Q denoting the ratios of reactance to resistance of said circuits respectively.

5. In a modulating system, a cavity magnetron oscillator, means responsive to a signal of modulated frequency for modulating said oscillator in a manner to produce therein a plurality of signal frequency components, at least one of which tends to be frequency-modulated in some degree in substantial accordance with the modulation of said signal, an auxiliary oscillator for producing a signal whose frequency approximates the mean frequency of said one component, means including a buffer amplifier for supplying signal from said auxiliary oscillator to said magnetron oscillator, whereby to reduce the tendency of said one component to be frequency-modulated and to impart to another of said components frequency variations according in some degree to the modulation of said one component which would have existed in the absence of said reduction, and means for deriving from said magnetron an output signal which varies in frequency in accordance with frequency variations in said other component.

6. In a modulating system, an oscillator having a tank circuit, means responsive to a signal of modulated frequency for controlling said oscillator in a manner to produce in said tank circuit a plurality of signal frequency components, at least one of which tends to be frequency-modulated in some degree in substantial accordance with the modulation of said signal, a resonant circuit coupled to said tank circuit, said resonant circuit having a Q substantially greater than the Q of said tank circuit, Q denoting the ratios of reactance to resistance of said circuits respectively, and being tuned to substantially the mean frequency of said one component and being adapted to reduce the tendency of said one component to be frequency-modulated and to impart to another of said components frequency variations according in some degree to the modulation of said one component which would have existed in the absence of said reduction, and means for deriving from said tank circuit an output signal which varies in frequency in accordance with frequency variations of said other component.

cordance with frequency variations of said other component.

7. In a modulating system, an oscillator having a tank circuit, means responsive to a signal of modulated frequency for controlling said oscillator in a manner to produce in said circuit a plurality of signal frequency components, at least one of which tends to be frequency-modulated in some degree in substantial accordance with the modulation of said signal, a resonant circuit tuned to substantially the mean frequency of said one component, means coupling said resonant circuit to said tank circuit in a manner to reduce the tendency of said one component to be frequency-modulated and to impart to another of said components frequency variations according in some degree to the modulation of said one component which would have existed in the absence of said reduction, said means having an admittance whose phase angle ϕ is substantially that given by the expression:

$$\phi = \tan^{-1} \frac{\omega_{22} - \omega_{11}}{\gamma_{11} - \gamma_{22}}$$

25 where ω_{11} is the resonant frequency of the loaded oscillator tank circuit, γ_{22} is the resonant frequency of said resonant circuit when loaded, γ_{11} is the half bandwidth of the loaded oscillator tank circuit and ω_{22} is the half bandwidth of said resonant circuit when loaded, and means for deriving from said tank circuit an output signal which varies in frequency in accordance with frequency variations of said other component.

8. In a modulating system, an oscillator having a tank circuit, means responsive to a signal of modulated frequency for controlling said oscillator in a manner to produce in said tank circuit a plurality of signal frequency components, at least one of which tends to be frequency-modulated in some degree in substantial accordance with the modulation of said signal, a tuned circuit resonant at substantially the mean frequency of said one component, means magnetically coupling said tuned circuit to said tank circuit whereby said tuned circuit is effective to reduce the tendency of said one component to be frequency-modulated and to impart to another of said components frequency variations according in some degree to the modulation of said one component which would have existed in the absence of said reduction, the magnitude of the magnetic coupling provided by said means being such as to maintain the relation:

$$\frac{Q_{20}}{Q_{22}} = 1 + \frac{Q_{10}}{Q_{11}}$$

55 where Q_{10} is the Q of the unloaded oscillator tank circuit, Q_{11} is the Q of the loaded oscillator tank circuit, Q_{20} is the Q of said last named resonant circuit when not loaded and Q_{22} is the Q of said last-named resonant circuit when loaded, Q denoting the ratios of reactance to resistance of said circuits respectively, and means for deriving from said tank circuit an output signal which varies in frequency in accordance with frequency variations of said other component.

9. In a modulating system, a source of a signal of predetermined frequency, a source of a second signal of modulated frequency, means including a tank circuit for mixing said first and second signals to yield a third signal comprising a plurality of frequency components, at least one of which tends to be frequency-modulated in some degree in substantial accordance with the frequency modulation of said second signal and

at least another of which is of substantially greater magnitude than said one component, a resonant circuit coupled to said tank circuit, said resonant circuit being tuned to substantially the mean frequency of said one component and being operative to reduce the tendency of said one component to be frequency-modulated and to impart to said other component frequency variations according in some degree to the modulation of said one component which would have existed in the absence of said reduction, and means for deriving from said oscillator an output signal which varies in frequency in accordance with the frequency variations in said other component.

10. In a modulating system, a source of a signal of predetermined frequency, a source of a second signal of modulated frequency, means including a tank circuit for mixing said first and second signals to yield a third signal comprising a plurality of frequency components, at least one of which tends to be frequency-modulated in some degree in substantial accordance with the frequency modulation of said second signal and at least another of which is of substantially greater magnitude than said one component, an auxiliary source of energy of a frequency closely approximating the mean frequency of said one component, means for supplying energy from said source to said tank circuit to reduce the tendency of said one component to be frequency-modulated, whereby there are imparted to said other component frequency variations according in some degree to the modulation of said second signal which would have existed in the absence of said reduction, and means for deriving an output signal which varies in frequency in accordance with the frequency variations of said other component.

11. In a modulating system, a source of a signal of modulated frequency, an oscillator having a resonant tank circuit, the half-bandwidth of said tank circuit when loaded being of the same order as the mean frequency of said frequency-modulated signal, means responsive to said signal for controlling said oscillator in a manner to produce, in the output from said oscillator, a plurality of frequency components, at least one of which tends to be frequency-modulated in some degree in substantial accordance with the modulation of said signal, a resonant circuit coupled to said tank circuit, said resonant circuit being tuned to substantially the mean frequency of said one component for substantially reducing the tendency of said one component to be frequency modulated, whereby there are imparted to another of said components frequency variations according in some degree to the modulation of said one component which would have existed in the absence of said reduction, and means for deriving an output signal which varies in frequency in accordance with the frequency variations of said other component.

12. In a modulating system, a source of a signal of modulated frequency, an oscillator having a resonant tank circuit, the half-bandwidth of said tank circuit when loaded being of the same order as the mean frequency of said frequency-modulated signal, means responsive to said signal for controlling said oscillator in a manner to produce, in the output from said oscillator, a plurality of frequency components, at least one of which tends to be frequency-modulated in some degree in substantial accordance with the modulation of said signal, an auxiliary source of energy of a frequency closely approximating the

mean frequency of said one component, means for supplying energy from said source to said tank circuit to reduce the tendency of said one component to be frequency-modulated, whereby there are imparted to another of said components frequency variations according in some degree to the modulation of said one component which would have existed in the absence of said reduction, and means for deriving an output signal which varies in frequency in accordance with the frequency variations of said other component.

13. In a modulating system, a source of a signal of predetermined frequency, a source of a second signal of modulated frequency, means including a tank circuit for mixing said first and second signals to yield a third signal comprising fundamental and sideband frequency components, said fundamental component being of appreciably greater magnitude than said sideband components and at least one of said sideband components having a tendency to be frequency-modulated in some degree in substantial accordance with the frequency modulation of said second signal, a resonant circuit coupled to said tank circuit, said resonant circuit being tuned to substantially the mean frequency of said sideband component for substantially reducing the tendency of said sideband component to be frequency-modulated, whereby there are imparted to said fundamental component frequency variations according in some degree to the modulation of said sideband component which would have existed in the absence of said reduction, and means for deriving an output signal which varies in frequency in accordance with the frequency variations of said fundamental component.

14. In a modulating system, a source of a signal of predetermined frequency, a source of a second signal of modulated frequency, means including a tank circuit for mixing said first and second signals to yield a third signal comprising fundamental and sideband frequency components, said fundamental component being of appreciably greater magnitude than said sideband components and at least one of said sideband components having a tendency to be frequency-modulated in some degree in substantial accordance with the frequency modulation of said second signal, an auxiliary source of energy of a frequency closely approximating the mean frequency of said sideband component, means for supplying energy from said source to said tank circuit to reduce the tendency of said sideband component to be frequency-modulated, whereby there are imparted to said fundamental component frequency variations according in some degree to the modulation of said sideband component which would have existed in the absence of said reduction, and means for deriving an output signal which varies in frequency in accordance with the frequency variations of said fundamental component.

15. In a modulating system, an oscillator having a tank circuit, means responsive to a signal of modulated frequency for controlling said oscillator in a manner to produce in said tank circuit a plurality of frequency components, at least one of which tends to be frequency-modulated in some degree in substantial accordance with the modulation of said signal and at least another of which is of substantially greater magnitude than said one component, an auxiliary source of energy of a frequency closely approximating the mean frequency of said one component, means for

supplying energy from said source to said tank circuit to reduce the tendency of said one component to be frequency-modulated, whereby there are imparted to said other component frequency variations according in some degree to the modulation of said one component which would have existed in the absence of said reduction, and means for deriving from said oscillator an output signal which varies in frequency in accordance with the frequency variations of said other component.

16. In a modulating system, an oscillator having a tank circuit, means responsive to a signal of modulated frequency for controlling said oscillator in a manner to produce in said tank circuit fundamental and sideband frequency components, said fundamental component being of appreciably greater magnitude than said sideband components and at least one of said sideband components having a tendency to be frequency-modulated in some degree in substantial accordance with the modulation of said signal, an auxiliary source of energy of a frequency closely approximating the mean frequency of said last-named sideband com-

ponent, means for supplying energy from said source to said tank circuit to reduce the tendency of said last-named sideband component to be frequency-modulated and to impart to said fundamental component frequency variations according in some degree to the modulation of said sideband component which would have existed in the absence of said reduction, and means for deriving from said tank circuit an output signal which varies in frequency in accordance with frequency variations of said fundamental component.
